(57) **CLAIM**

The ornamental design for a recessed lighting fixture, as shown and described.

DESCRIPTION

FIG. 1 is a perspective view of a recessed lighting fixture showing the new design;

FIG. 2 is a front view thereof;

FIG. 3 is a rear view thereof;

FIG. 4 is a right side view thereof, the left side view being a mirror image of the right side view;

FIG. 5 is a top view thereof;

FIG. 6 is a bottom view thereof;

FIG. 7 is an end elevational view in section taken along line 7—7 in FIG. 2 with the internal parts omitted; and,

FIG. 8 is a reference drawing for showing the recessed lighting fixture embedded in the ceiling.

The broken lines in the drawings depict unclaimed environmental subject matter.

It is certified that error appears in the above-identified patent and that said Letters Patent is hereby corrected as shown below:

Please delete the title page and insert the title page showing an illustrative figure as attached.

In the Drawings

Please Delete drawing sheets 1- 8 and insert drawing sheets 1-8 with figures 1-8 as attached.

Signed and Sealed this
Twenty-first Day of May, 2013

Teresa Stanek Rea
Acting Director of the United States Patent and Trademark Office
